CLAIM

The ornamental design for a lighting device, as shown and described.

DESCRIPTION

A portion of the disclosure of this patent document contains or may contain material which is subject to copyright protection. The copyright owner has no objection to the photocopy reproduction by anyone of the patent document in exactly the form it appears in the Patent and Trademark Office patent file or records, but otherwise reserves all copyrights whatsoever.

FIG. 1 is a front elevation view of a first embodiment of the lighting device.

FIG. 2 is a rear elevation view of the first embodiment of the lighting device.

FIG. 3 is a left side elevation view of the first embodiment of the lighting device.

FIG. 4 is a right side elevation view of the first embodiment of the lighting device.

FIG. 5 is a top view of the first embodiment of the lighting device.

FIG. 6 is a bottom view of the first embodiment of the lighting device.

FIG. 7 is a top, right isometric view of the first embodiment of the lighting device.

FIG. 8 is a bottom isometric view of the first embodiment of the lighting device.

FIG. 9 is a front elevation view of a second embodiment of the lighting device.

FIG. 10 is a rear elevation view of the second embodiment of the lighting device.

FIG. 11 is a left side elevation view of the second embodiment of the lighting device.

FIG. 12 is a right side elevation view of the second embodiment of the lighting device.

FIG. 13 is a top view of the second embodiment of the lighting device.

FIG. 14 is a bottom view of the second embodiment of the lighting device.

FIG. 15 is a top, right isometric view of the second embodiment of the lighting device; and,

FIG. 16 is a bottom isometric view of the second embodiment of the lighting device.

The broken lines in the drawings illustrate portions of the lighting device which form no part of the claimed design.

1 Claim, 16 Drawing Sheets
